CLAIM

The ornamental design for an embroidery machine, as shown and described.

DESCRIPTION

FIG. 1 is a top, front and left side perspective view of an embroidery machine showing my new design; FIG. 2 is a top, front and right side perspective view thereof; FIG. 3 is a bottom, front and left side perspective view thereof; FIG. 4 is a bottom, front and right side perspective view thereof; FIG. 5 is a front elevational view thereof; FIG. 6 is a rear elevational view thereof; FIG. 7 is a left side view thereof; FIG. 8 is a right side view thereof; FIG. 9 is a top plan view thereof; FIG. 10 is a bottom plan view thereof; FIG. 11 is an enlarged view of portion 11 in FIG. 1; FIG. 12 is an enlarged view of portion 12 in FIG. 1; FIG. 13 is an enlarged view of portion 13 in FIG. 1; and, FIG. 14 is an enlarged view of portion 14 in FIG. 5. The broken lines with even breaks in the drawings illustrate portions of the embroidery machine which form no part of the claimed design.

The oblique lines in the drawings represent reflective surfaces.

1 Claim, 14 Drawing Sheets
